United States Patent Office

Des. 201,062
Patented May 4, 1965

201,062

SUPersonic AIRPLANE

Clarence L. Johnson, Encino, and William H. Statler,
Northridge, Calif., assignors to Lockheed Aircraft Cor-
poration, Burbank, Calif.

Filed May 15, 1964, Ser. No. 79,994

Term of patent 14 years

(Cl. D71—1)

FIG. 1

Des. 201,062

PAGE 2

FIG. 2

FIG. 3

Fig. 4

FIGURE 1 is a perspective top view of a supersonic airplane, showing our new design;

FIGURE 2 is a side elevational view thereof;

FIGURE 3 is a front elevational view thereof; and

FIGURE 4 is a bottom view thereof.

The dominant features of our design reside in those portions shown in full lines.

We claim:

The ornamental design for a supersonic airplane, as shown and described.
